TELEPHONE DIAL ATTACHMENT

Lucy Cotton, Miami, Fla.

Application June 6, 1945, Serial No. 597,776

4 Claims. (Cl. 179—90)

1

The present invention relates to an attachment for telephones, and more particularly a dial telephone provided with a rotatable disc having holes therein for manipulating the dial.

In the use of an automatic type telephone the disc is usually rotated by inserting a finger in one of the holes of the dial corresponding to the symbol which is seen through one of the holes of the dial. The dial is then rotated until the dial is arrested by a fixed stop member. The visibility of the symbols is not always clear, and the telephone instrument is often arranged in positions where ordinary illumination is not sufficient to make the symbols or numbers easily discernible. The present invention provides the solution to this problem and avoids the necessity of employing artificial light even when the telephone is used at night.

An object of the invention is to provide an attachment for the dial of a telephone having luminous symbols thereon which may be readily observed in the dark, including a novel arrangement whereby the device may be readily attached to a conventional telephone instrument without removing or changing any of the parts thereof.

Another object of the invention is to provide an attachment for the dialing mechanism of a telephone wherein the symbols associated with the dial may be more readily observed, including a structural arrangement for preventing rotation of the attachment relative to the telephone equipment.

Other objects and features of the invention will be more apparent as the disclosure proceeds and upon consideration of the following detailed description and the appended drawing wherein an exemplary embodiment of the invention is disclosed.

In the drawing:

Fig. 1 is a plan view of a conventional type telephone with parts of the dial broken away and illustrating an attachment embodying the invention associated with the instrument partly in section.

Fig. 2 is an elevational view of the telephone dialing mechanism showing the attachment in section taken on the line 2—2 of Fig. 1.

Fig. 3 is a side elevational view of the apparatus shown in Fig. 1.

Referring to the drawing, there is shown at 10 the base of a telephone of a conventional dial type in present use. The base of the telephone is provided with a cushion 11 on the bottom thereof which may be formed of felt or other materials to prevent scratching or marring of the surface

on which the telephone instrument is supported. The base 10 carries a rotatable disc 12 of conventional construction and provided with a number of openings or holes for rotating the dial.

5 The central portion of the dial 12 is provided with a number plate 14. The dialing mechanism includes an annular surface 16 arranged around a stationary collar 17, and the surface 16 carries symbols which may be seen through the openings 10 18 in the dial or disc. A finger stop 19 extends from a fixed portion of the telephone instrument and overlies the dial 12 so as to arrest rotation of the dial. The stop member 19 may be fixed to a stationary part of the telephone instrument in 15 any conventional manner and is preferably attached thereto by means of screws 21. The elements of the telephone thus far described represent those of a conventional telephone instrument, and the attachment for facilitating the 20 operation of the dial may be applied to such a telephone without changing or altering any of the parts thereof.

A device exhibiting the invention is adapted to be arranged around the collar 17 and cover the 25 symbols arranged on the annular surface 16. The attachment includes two arcuate sections 26 and 27, as shown in Fig. 1. The section 26 comprises an arcuate shaped frame having an outer bead 28 and an inner arcuate bead 29. 30 This frame is designed to support an arcuate shaped plate 31 carrying thereon the symbols corresponding in spacing and arrangement to those of a conventional telephone dial mechanism and which are normally on the annular surface 16. The curved arcuate shaped plate 31 may be formed of any suitable material, such as metal, Celluloid, or the like, having stamped or printed thereon the symbols for the telephone dial in luminous material, such as phosphorescent paint 35 or radiant salt combinations. The luminous material may be covered with a transparent sheet or layer to protect the symbols from contact with the finger, or other objects used in dialing. The lower arcuate shaped section 27 likewise includes 40 inner and outer beads which are substantially U-shaped in cross section, and within which an arcuate symbol plate 32 may be supported. The inner and outer beads of the lower section 27 are connected by end portion 35 which lies along 45 50 and is parallel to a similar end portion 38 of the upper section 26. The other ends of the arcuate sections 26 and 27 are joined by a small plate 39. This plate 39 may be secured to the adjacent ends of the arcuate sections by means of screws, 55 as shown in Fig. 1.

The dial attachment includes a socket for supporting an elongated instrument 41 which may be used for actuating the dial 12. The socket is cup-shaped and preferably formed of two hemicylindrical shaped parts 42 and 43. The two-part socket is supported by arms 44 and 46 which project from the sections 27 and 26 on opposite sides of the stop member 19. The two parts of the socket member may be formed integral with the arms 44 and 46, or attached thereto in any suitable manner, such as by welding. The socket member is flared outwardly at the upper end, as shown in the drawing, and is provided with slots 47 so as to increase the resiliency of the socket member. The instrument 41 for actuating the dial 12 may be introduced into the socket and resiliently held therein simply by moving the instrument downwardly into the outwardly flared upper ends. As shown in Fig. 2, the dialing key 41 may be provided at its dial penetrating end, with a dial engaging groove or slot 45 which preferably extends only part way around the periphery of the key 41. This slot 45 on insertion of key 41 in one of the operating holes of disc 12 especially one of such holes spaced more than 180° from the stop 19, engages over the side edge of said hole throughout a part of the turning movement of the elements, thus preventing slipping of the keying device from the holes and reducing the necessity for re-dialing. As the dial is rotated, in the preferred manner of use, the key 45 turns relative to the disc 12, and the groove 45, in the preferred form, disengages from the disc edge by the time the finger stop 19 is reached so that the key may be easily lifted from the finger opening. The dialing instrument 41 is also connected to the base of the telephone instrument by a flexible element, such as a chain 51, so that the dialing instrument will not become completely separated from the telephone instrument. As shown in Fig. 3 the attachment is provided with a projection or loop 48, shown secured to the socket member 42 below the flared part thereof, to which the chain 51 may be attached, or to which a pencil may be attached if the chain is otherwise secured, as by one of the screws 21 which attach the finger stop 19, as shown.

The dial attachment may be arranged on the telephone by bending or springing the upper arcuate section 26 away from the lower arcuate section 27. This outward opening of the two sections is made possible by means of a flexible plate 53 which joins the two parts of the socket member. When the upper arcuate section 26 is moved away from the lower arcuate section 27, the finger stop 19 may be introduced in the opening provided between the arms 44 and 46 and the dial attachment may be arranged around the collar 17. The finger stop 19 may then be secured to the telephone instrument by inserting the screws 21 if it has been removed to facilitate the assembly or provide for attachment of chain 51. The plate 53 may then be attached to hold the adjacent ends of the two sections 26 and 27 together whereby the inner beads of the two sections fit snugly about the collar 17. When the ends of the two sections are joined by the plate 53, the arms 44 and 46 are adjacent the extremities of the finger stop 19 and thus prevent rotation of the dial attachment relative to the supporting base 10. The movement of the arcuate sections 26 and 27 towards each other is made possible by the flexibility of the plate 53 which may be welded or otherwise secured to the

two parts of the socket member. The arms 44 and 46 also support the socket member adjacent the finger stop 19 so that the instrument 41 for actuating the dial 12 is supported in a convenient position with reference to the telephone

5

socket member 53 to form a unitary hinged structure fulcruming about a point adjacent the finger stop 19, and that when the device is positioned on the telephone instrument and anchored by the securing means 39, this means is located inconspicuously under the rotatable disc where it is not apt to be tampered with. By this arrangement the protrusion of clamp screws and the like into positions where they might injure the finger of the user is avoided, and a smooth, neat assembly is attained.

In the drawing: In Fig. 2 apply the reference numeral 45 to the notch in member 41 which lies just above reference numeral 46; and in Fig. 3 apply reference numeral 48 to the projection from element 42 which lies between reference numerals 42 and 53.

While the invention has been described with reference to specific structural details, it is to be understood that changes may be made therein by those skilled in the art. Such modifications and changes in the materials employed in the dial attachment may be made without departing from the spirit and scope of the invention as set forth in the appended claims.

35 I claim:

1. An attachment for rotary dial telephones of the type having finger holes and a finger stop for effecting predetermined rotations of the dial thereof, said attachment comprising a hinge member, means carried by said hinge member adapted in the closed position thereof to embrace said finger stop, means carried by those portions of said finger stop embracing means remote from said hinge member adapted in the closed position thereof to embrace a stationary part of the telephone underlying the dial, and means associated with the ends of said last named means most remote from said hinge member and positioned to underlie the rotatable dial portion of the telephone for holding said parts in the closed position thereof to secure the attachment to the telephone.

2. An attachment for rotary dial telephones of the type having a finger rotated dial and a finger stop, said attachment comprising a hinge means, and elements located progressively further from the hinge means for embracing a dial operating instrument, the finger stop of the telephone and a structural part of the telephone underlying the rotary dial thereof, means positioned to underlie the dial of the telephone to secure said attachment thereto, said attachment embracing the dial operating instrument releasably.

3. An attachment for dial telephones of the type having a finger moved dial and a finger stop, said attachment comprising a hinge means, and elements carried by said hinge means for embracing a dial operating instrument and the finger stop of the dial, said attachment embracing the dial operating instrument releasably so that it may be removed therefrom for insertion in the finger moved dial to facilitate movement of the latter, said instrument embracing means comprising a resilient socket carried by said hinge means, and said dial operating instrument com-

prising a removable keying member frictionally engaged in said socket, adapted on removal therefrom to enter the finger apertures of the finger moved dial, and provided with a flexible securing means for attaching it to the telephone as a part of the attachment assembly.

4. An attachment for dial telephones of the type having a finger moved dial and a finger stop, said attachment comprising a hinge means, and elements carried by said hinge means for embracing a dial operating instrument and the finger stop of the dial, said attachment embracing the dial operating instrument releasably so that it may be removed therefrom for insertion in the finger moved dial to facilitate movement of the latter, said instrument embracing means comprising a socket carried by said hinge means, and said dial operating instrument comprising a removable keying member engaged in said socket

and adapted on removal therefrom to enter the finger apertures of said finger moved dial, and having a groove extending partway around its periphery adapted to hook in the finger apertures during a portion of the rotation of the dial.
